US0D1073878S

(12) **United States Design Patent** (10) **Patent No.:** **US D1,073,878 S**
(45) **Date of Patent:** **** May 6, 2025**

(54) **RETURN LINE CONNECTOR**

(71) Applicant: **Jianfeng Gao**, Anqiu (CN)

(72) Inventor: **Jianfeng Gao**, Anqiu (CN)

(**) Term: **15 Years**

(21) Appl. No.: **29/969,271**

(22) Filed: **Oct. 22, 2024**

(51) **LOC (15) Cl.** **23-01**

(52) **U.S. Cl.**
USPC **D23/262**

(58) **Field of Classification Search**

(57) **CLAIM**

The ornamental design for a return line connector, as shown and described.

DESCRIPTION

FIG. 1 is a front perspective view of a return line connector, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the return line connector, which form no part of the claimed design.

1 Claim, 8 Drawing Sheets
